UNITED STATES PATENT OFFICE.

GUSTAV KAFFENBERGER, OF HAMILTON, OHIO.

DRIVE FOR PAPER-MAKING MACHINES.

SPECIFICATION forming part of Letters Patent No. 293,471, dated February 12, 1884.

Application filed November 15, 1883. (No model.)

To all whom it may concern:

Be it known that I, GUSTAV KAFFENBERGER, of Hamilton, Butler county, Ohio, have invented certain new and useful Improvements in 5 Drives for Paper-Making Machines, of which the following is a specification.

This invention pertains to mechanism for transmitting the driving motion from the main driving-shaft of a paper-making machine to 10 such machine, and for permitting of the adjustment of the relative speeds of the various parts, as hereinafter fully set forth.

In the accompanying drawings, Figure 1 is 15 a side view of portions of a paper-making machine fitted with my improved drive; Fig. 2, a transverse section of the same near one of the presses, and Fig. 3 a plan of the idler-carrier and its adjusting mechanism.

In the drawings, A represents a portion of 20 the Fourdrinier part of a paper-making machine; B, the coupler; C, the first press; D, the second press; E, a portion of the drier part; F, the framing of the machine; G, roll-stands, and H rolls, all constructed and arranged as usual.

I represents a line-shaft or main driving-shaft placed parallel to the paper-making machine, near the floor, and as close against the side of the machine-framing as its operation 25 will permit; J, bevel-gears on the parts of the paper-making machine to which motion is to be given from the shaft I; K, bevel-pinion shafts at each of said bevel-gears; L, bevel-pinion shafts on said shaft and engaging said bevel-gears; M, a conical drum on each bevel-pinion shaft; N, conical drums on the line-shaft at positions to correspond with the drums M, and arranged with their tapers oppositely disposed with reference to the taper 35 40 of the drums M; O, floor stands or housings furnishing bearing-supports for the line-shaft and for the bevel-pinion shafts; P, friction-idlers arranged to be held in contact with the conical drums and transmit the motion from 45 the drums upon the line-shaft to the drums upon the bevel-pinion shafts; Q, carriers in which the idlers are journaled; R, screws loosely journaled in the floor-stands, across 50 which they pass, and engaging with their threads the carriers; S, a rod reaching from

the carrier backward across the machine-frame; T, a handle on the rear end of the rod S; U, a nut-holder secured to the rear side of the machine-frame at the end of the rod S; V, a nut upon the threaded part of the rod held 55 in the nut-holder, and W collars upon the screws R, engaging one of the floor-stands, to prevent end motion of the screw.

A pair of the conical drums, &c., is supplied at each portion of the paper-making machine 60 whose relative velocity of motion is to be altered in adjusting the tension of the paper. The line-shaft runs at high velocity, to transmit motion through the drums, idlers, and bevel-gears to the different parts. The relative velocity of 65 the two drums of each pair will be governed by the position of the idler, in an obvious manner, and this position may be adjusted and altered by means of the screw R, which traverses the idler along the face of the drums, whereby 70 the different portions of the paper-making machine may have different speeds of rotation while receiving motion from a single line-shaft, and the speeds of the parts may be adjusted 75 while the machine is at work. The idlers are 80 held into forcible contact with the drums by the strain of the screw-rods S. By turning the handle T in one direction the idler will be brought into forcible contact with the drums, and by turning the handle in the other direction the idler is relieved from its forcible contact, and the upper cone ceases its motion. The device thus serves as a means for stopping 85 and starting the parts of the machine as well as for adjusting the speed.

The screw R, while it engages the floor-stands, is carried in bearings of such size as not in the least to interfere with the movements of the carrier as the idler is adjusted to or away from the drums.

The rod S is connected to the carrier by a joint-pin, X, as shown, and the nut V is articulated in its holder, as shown, whereby the rod does not in any manner interfere with the traversing motion of the carrier.

The line-shaft may receive its motion from a motor through any suitable means, and tangent-gearing may be substituted for the bevel-gearing, if desired.

I show the bevel-pinion shafts arranged ver-

85

100

tically over the line-shaft; but such arrangement is not at all essential. The bevel-pinion shafts may be disposed as found most convenient as to height and position with reference to the line-shaft, and the bevel-pinion shafts do not need to be arranged uniformly.

While I entitle my invention as a "drive for paper-making machines," and while I illustrate it in connection with paper-making machines, I do not limit my invention to use with paper-making machines. On the contrary, I contemplate its application to any longitudinal series of independently-driven machine parts, as hereinafter distinctly pointed out.

15. I claim as my invention—

1. The combination of a longitudinal series of machine parts to be independently driven, a line-shaft disposed parallel to such series of machine parts, a drum upon said line-shaft at 20 each of said parts, a short shaft parallel to the line-shaft at each of said machine parts, connected thereto by gearing and provided with a drum, a friction-idler at each of the pairs of

drums, and means for adjusting the idlers to and from the drums in starting and stopping 25 of the machine parts, substantially as and for the purpose as set forth.

2. The combination of a longitudinal series of machine parts to be independently driven, a line-shaft disposed parallel to such series of 30 machine parts, and provided with conical drums, a short shaft disposed parallel to said line-shaft at each of said machine parts, connected thereto by gearing and provided with a conical drum, a friction-idler arranged to 35 be held into forcible contact with each of the pairs of conical drums, and a means for adjusting said idlers along the faces of said conical drums in regulating the speed of the machine parts, substantially as and for the purpose specified.

GUSTAV KAFFENBERGER.
